UNITED STATES PATENT OFFICE.

EDWARD F. BREDEHOFT, OF ST. LOUIS, MISSOURI, ASSIGNOR TO GEO. D. BARNARD & COMPANY, A CORPORATION OF ILLINOIS.

FILE-BOX.

1,228,743.

Specification of Letters Patent.

Patented June 5, 1917.

Application filed October 23, 1916. Serial No. 127,131.

To all whom it may concern:

Be it known that I, EDWARD F. BREDEHOFT, of the city of St. Louis, State of Missouri, have invented certain new and useful 5 Improvements in File-Boxes, of which the following is a full, clear, and exact description, reference being had to the accompanying drawings, forming a part of this specification. 10 My invention relates to a file box adapted to contain loose cards or sheets, such for example as account sheets forming part of the bookkeeping system of a bank. One of the objects of the invention is to provide an improved means for connecting a closure to the receptacle containing the filed sheets. Another object is to produce a file box having a closure movable to expose the upper edges of the file sheets and a side wall member 15 movable to expose the side edges of the sheets, thereby admitting light into the box at the top and side so that the sheets may be readily inspected. A further object is to produce a file box having tilttable back members 20 between which the filed sheets are confined, one of said tilttable back members being adjustable to compensate for variations in the dimensions of the filed matter, and an adjustable follower adapted to engage the 25 adjustable back member. The tilttable back members constitute inclined supporting elements for the filed sheets, as will be herein- 30 after described.

With the foregoing and other objects in view the invention comprises the novel construction, combination and arrangement of parts hereinafter more specifically described and illustrated in the accompanying drawings wherein is shown the preferred embodiment 40 of the invention; however, it is to be understood that the invention comprehends changes, variations and modifications which come within the scope of the claims hereunto appended.

Figure I is a vertical section of a file box constructed in accordance with the invention.

Fig. II is a plan view of the box, the closure being shown in section.

Fig. III is a transverse section, the upper portion of the closure being broken away.

Fig. IV is a fragmentary section illustrat-

ing the follower and the guide rods to which said follower is slidably fitted.

Fig. V is a fragmentary detail view showing the latch device for securing the hinged side wall member in its closed position.

Fig. VI is a vertical section on line VI—VI, Fig. V.

Fig. VII is a view, partly in vertical cross section, and partly in elevation of the connection between the file box and its closure.

A designates a receptacle adapted to receive the sheets or cards B. A closure C is adapted to overlie the filed sheets, as indicated by broken lines at the upper portion of Fig. I, and this closure may be shifted to the open position shown by full lines in Figs. I, II and III.

The means for connecting the closure to the receptacle A comprises a hinge device including a pair of hinge members 1 pivoted at 2 to the rear wall of the receptacle. Guide rods or bars 3, arranged within and fixed to the side walls of the closure, are slidably mounted in tubular portions of the hinge members 1. These guide rods 3 are arranged at a right angle to the axis of the hinges. When the closure occupies the closed position, shown by broken lines in Fig. I, it may be lifted about the axis of the hinge members 1 and then moved downwardly at an angle to said axis, so as to occupy the open position shown by full lines in Fig. I. It will be observed that the guide rods 3, slidably fitted to the hinge members 1, allow the closure to move at a right angle to the axis of the hinge. When the closure occupies its open position, it does not extend a very great distance from the rear of the receptacle, and this is an advantage in a large file box constructed in accordance with the invention. Furthermore, the closure is dropped to such an extent at the rear of the receptacle that it does not materially interfere with the admission of light to the filed sheets.

The front and rear walls of the receptacle are preferably provided with handles 4, and a similar handle 5 is secured to the front of the closure.

A side wall member 6, extending approximately from one end of the receptacle to the other, is hinged at 7, and it may be dropped

from the position shown by full lines in Fig. III to the position shown by dotted lines, so as to expose the side edges of the filed sheets. This provides for the admission of 5 light at one side of the receptacle so that the matter written or printed on the sheets may be easily inspected.

The means for securing the hinged wall member 6 in its elevated position comprises 10 a latch member 8 (Figs. II, V and VI) pivoted to the inner face of said wall member and adapted to overlap a fixed part 9 of the receptacle. A spring 10, surrounding the latch pivot, tends to retain the latch 15 member 8 in its operative position, but said latch member may be easily turned on its pivot to unlock the hinged wall member. When the closure C occupies its closed position, its lower edge overlaps the upper 20 edge of the hinged wall member 6, so as to securely hold said wall member in its closed position.

F designates a follower having a pair of tubular arms 12 at its sides, said arms being 25 slidably mounted on a pair of horizontal guide rods 13 at the opposite sides of the filed sheets. The follower F is adjustable along the guide rods 13. The means for securing the follower comprises a pair detents 30 14 (Figs. II and IV) pivoted at 15 to the follower and provided with cam faces adapted to engage the guide rods 13. Pull rods 16 connect the detents 14 to operating members 16, the latter being movable toward 35 each other to disengage the pivoted detents from the guide rods 13. 18 designates compression springs for forcing the pivoted detents into engagement with the guide rods 13.

40 The filed sheets are arranged between tiltable back members 19 and 20 (Figs. I, II and III), said back members being preferably made of sheet metal or other suitable material. The tiltable back member 19 is 45 fastened to the bottom wall of the receptacle by means of hinges 21 (Fig. I), and it is free to swing from the inclined position shown by full lines in Fig. I to the substantially vertical position shown by dotted lines. A filler 22 (Figs. I and II) hinged to 50 the front wall at 23, is adapted to occupy the elevated position shown by full lines in Fig. I, wherein it allows the back member 19 to occupy an inclined position, and this 55 filler 22 may be moved downwardly to the position shown by dotted lines to retain the back member in its vertical position. When the filed sheets are to be inspected, the hinged filler 22 is placed in the elevated position shown in Fig. I. Before closing the 60 receptacle, the filler 22 is shifted downwardly about the axis of its hinge 23, to the position shown by dotted lines in Fig. I, and the follower F is then adjusted along 65 the rods 13 to secure the filed sheets in the

compact condition indicated by dot and dash lines in Fig. I.

The tiltable back member 20 at the rear of the filed sheets is adjustably supported by a pair of corrugated retaining devices 24, each having a series of recesses adapted to receive a leg 20' at the lower edge of the back member 20. When the filed sheets are separated for manipulation, as shown in Fig. I, the back member 20 is tilted rearwardly and 70 engaged with the follower F, thus retaining a body of the sheets in an inclined condition so that the sheet at the front of the collection may be readily manipulated. It will be noted that the follower F may be 75 adjusted to compensate for variations in the dimensions of the collection of filed sheets, and the tiltable back member 20 may be adjusted along the corrugated members 24 to a predetermined position with respect to the 80 adjustable follower.

The lower edges of the filed sheets are 85 slidably fitted to a supporting device which 90 consists of a pair of tracks 25 adapted to be engaged by the lower edges of the sheets. As shown in Fig. I, each of the tracks is inclined downwardly in opposite directions 95 from a point near the transverse center line of the receptacle, the object being to firmly support the separated bodies of sheets in oppositely inclined positions. This holds the separated sheets away from each other and retains them in desirable positions for inspection.

The tracks 25 have ribs 26 (Fig. III) 100 adapted to enter notches in the lower edges of the sheets. Each sheet is provided with a pair of notches 27, so that it may be shifted to the right from the position shown in Fig. III, and then seated on the ribs 26. This 105 allows any selected sheet to be placed in an abnormal position for future reference.

I claim:—

1. A file box comprising a receptacle for the matter to be filed, a closure for said receptacle, a hinge for said closure, and a closure guide associated with said hinge and arranged to allow the closure to move transversely to the axis of the hinge, said closure being movable upwardly from its closed position, about the axis of the hinge, and then downwardly transversely to said axis.

2. A file box comprising a receptacle for the matter to be filed, a hinge secured to said receptacle, and a closure slidably connected to said hinge, said closure being movable upwardly about the axis of said hinge and then downwardly transversely to said axis.

3. A file box comprising a receptacle for the matter to be filed, a hinge device including a hinge member pivoted to said receptacle, a closure for said receptacle, and a closure guide secured to said closure and

- slidably fitted to said hinge member so as to allow the closure to move upwardly about the axis of said hinge member and then downwardly transversely to said axis.
5. 4. A file box comprising a receptacle for the matter to be filed, a hinge device pivoted to said receptacle, a closure for said receptacle, guide rods secured to said closure and slidably fitted to said hinge device, said 40
10 guide rods being arranged at a right angle to the axis of said hinge device.
5. A file box comprising a receptacle for the matter to be filed, a hinge device including a pair of hinge members pivoted to 45
15 said receptacle, a pair of guide rods slidably fitted to said hinge members, said guide rods being arranged at a right angle to the axis of the hinge members, and a closure secured to said guide rods.
20. 6. A file box comprising a receptacle for the sheets to be filed, a follower adjustably mounted in said receptacle, a tiltable back member arranged to lie between said follower and the filed sheets, and a retaining 50
25 device to which said tiltable back member is adjustably secured, said tiltable back member being movable toward and away from said follower and adjustable to different 55 positions along said retaining device.
30. 7. A file box comprising a receptacle for the sheets to be filed, a follower adjustably mounted in said receptacle, a tiltable back member arranged to lie between said follower and the filed sheets, and a retaining 60
35 device having a row of recesses adapted to receive the lower edge of said tiltable back member, the latter being adjustable from one recess to another, and said tiltable back 65
65 member being free to swing toward said follower to form an inclined supporting element for the filed sheets.
8. A file box comprising a receptacle for the sheets to be filed, a follower adjustably mounted in said receptacle, a tiltable back member arranged to lie between said follower and the filed sheets, and corrugated retaining members arranged below the plane of the filed sheets and adapted to receive the lower edge of said tiltable back member, the latter being adjustable along 50
45 said corrugated retaining members and also free to swing toward said follower to form an inclined supporting element for the filed sheets.
9. A file box comprising a receptacle for the sheets to be filed, a pair of tiltable back members arranged in said receptacle, said tiltable back members being so arranged that the filed sheets will be confined between them, a hinge securing the lower edge of one 60
65 of said tiltable back members to said receptacle, the other tiltable back member being adjustable to different positions to compensate for variations in the dimensions of the body of filed sheets, and an adjustable follower fitted to the last mentioned back member.
10. A file box comprising a receptacle for the sheets to be filed, a tiltable back member arranged to form an inclined supporting element for the filed sheets, a filler associated with said tiltable back member, and a pivot supporting said filler, said filler being adapted to retain the tiltable back member in a substantially vertical position. 70
75

EDWARD F. BREDEHOFT.
